Application filed November 13, 1895. Serial No. 568,866. Term of patent 7 years.

To all whom it may concern:

Be it known that I, THEODORE CHAMBERLAIN COMBES, a citizen of the United States, residing at Philadelphia, in the county of Philadelphia, State of Pennsylvania, have invented a new and original Design for a Badge or Similar Article, of which the following is a specification, reference being had to the accompanying drawing.

5 In the drawing is shown an enlarged plan view of my design.

The leading feature of my design consists of a tiger's head bearing or carrying a flag in

its mouth. The flag is usually in one or more colors and may bear appropriate words or devices. For illustration I have shown the flag in two colors.

What I claim as new, and desire to secure by Letters Patent, is—
